CLAIM

The ornamental design for a mouthwash dispenser, as shown and described.

DESCRIPTION

FIG. 1 is a front perspective view of a mouthwash dispenser, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof, and,

FIG. 8 is in its stored configuration.

The dashed broken lines depict portions of the mouthwash dispenser that form no part of the claim design.

1 Claim, 8 Drawing Sheets
